(57) **CLAIM**

The ornamental design for a bench, as shown and described.

DESCRIPTION

FIG. 1 is a perspective view of a bench showing my new design;

FIG. 2 is a front elevational view thereof;

FIG. 3 is a side elevational view, the opposite side being a mirror image thereof; and,

FIG. 4 is a top view thereof.

The views of the bench not shown form no part of the claimed design. The broken lines depicting a tunic, leg lacings, stretcher bars, and nail heads represent environmental elements only and form no part of the claimed design.
